SAFETY RAZOR

Paul J. Graybill, New Haven, Conn.

Application May 5, 1950, Serial No. 160,119

14 Claims. (Cl. 30—60.5)

1

The present invention relates in general to safety razors and more especially to an improved safety razor of the type wherein a blade may be assembled therewith and removed therefrom without the necessity for disassembling the several parts of the razor.

An object of the invention is to provide a safety razor of durable and economical construction and one which may be used and cleaned with facility and dispatch.

A further object of the invention is to provide a safety razor with pivoted blade-clamping means operable manually for clamping a blade to and for permitting removal of a blade from the safety razor without disassembling the several parts thereof.

A still further object of the invention is to provide a safety razor of the type hereinabove described having improved manually-operated means for swinging the blade-clamping means to and from blade-clamping position.

Other objects and advantages will appear to those skilled in the art from the following, considered in conjunction with the accompanying drawings.

In the accompanying drawings, in which certain modes of carrying out the present invention are shown for illustrative purposes:

Fig. 1 is an enlarged side elevation in longitudinal section of the improved safety razor of this invention showing the blade clamped between the blade-supporting member of the razor-head and the blade-clamping means;

Fig. 2 is an enlarged front elevation in longitudinal section of the razor on line 2—2 of Fig. 1;

Fig. 3 is an enlarged side elevation in longitudinal section of the razor showing the blade-clamping means elevated relative to the blade-supporting member of the razor-head for removing the blade therefrom;

Fig. 4 is an enlarged plan view in section of the razor-head on section line 4—4 of Fig. 1;

Fig. 5 is a plan view in section of the head of the razor on line 5—5 of Fig. 1;

Fig. 6 is a detached perspective view of one of the blade-clamps of the razor;

Fig. 7 is a detached perspective view of the elevating-cup for raising the blade-clamps of the razor;

Fig. 8 is a detached perspective view of the shaft of the clamp-operating means;

Fig. 9 is a detached perspective view of the crest-plate which is adapted to be riveted or otherwise secured on the upper end of the shaft;

2

Fig. 10 is a detached perspective view of the yoke for pivotally mounting the blade-clamps in the head of the razor; and

Fig. 11 is a perspective view of a razor blade to be utilized with the razor of this invention.

Referring particularly to Figs. 1 and 2, the safety razor of this invention comprises, in the main, a tubular handle 15 having a head 16 secured to the upper end thereof and comprising a blade-supporting member or guard 17, and blade-clamping means indicated generally at 18 arranged normally to clamp a blade to the blade-supporting member 17, the blade-clamping means being actuated by manually-operable means 19 mounted on the lower end of the handle 15.

The aforesaid blade-supporting member 17 comprises an elongated substantially-rectangular plate having a longitudinally-extending slightly-convex embossment on its upper surface on which the blade 21 of the razor is adapted to be clamped; and notches 22 at the corners of the embossment. Formed between each edge of the blade-supporting plate and the corresponding outer edge of the embossment is a longitudinal slot 23. A substantially-rectangular aperture is formed centrally of the blade-supporting plate 17 for accommodating the upper end of a well 25, the upper end of which is staked or fixedly secured in a similar manner in the aforesaid aperture of the blade-supporting plate. The well 25 projects from the underside of the blade-supporting plate 17 and comprises a substantially-rectangular cup-shaped element having oppositely-disposed side walls 26—26; oppositely-disposed end walls 27—27; and a substantially-rectangular bottom 28, the latter being provided with a substantially-central aperture 29, as shown especially well in Figs. 1, 2 and 3.

The blade-supporting member 17 and its well 25 constitute elements of the razor-head 16 to which the upper end of the handle 15 is secured by staking, soldering or otherwise securing the latter in the aperture 29 in the bottom of the aforesaid well 25.

The tubular handle 15 is substantially cylindrical throughout its length and is provided on its exterior surface with knurling to facilitate gripping the handle. Intermediate the opposite ends of the handle is an annular indenture 30 which is adapted to rotatably anchor the operating-means 19 in the handle in the manner hereinafter described, to prevent the operating-means 19 from moving longitudinally therein.

Referring especially to Figs. 1, 2 and 3, the aforesaid operating-means 19 of the blade-clamp-

ing means 18 comprises a shaft 31 rotatably mounted in the handle 15 and provided at its lower end with external threads 32 which are adapted to threadedly engage in corresponding internal threads, preferably of double pitch, formed in the upper end of a substantially-cylindrical hollow shank-portion 33 of an operating-nut 34, which constitutes an enlargement on the lower end of the shank 33, the operating-nut forming with its shank 33 an annular external shoulder 35 which is adapted to abut against the lower end of the handle and to be held in engagement therewith by means of the aforesaid annular indenture 30, the inwardly-projecting rib of which engages in an annular groove 36 formed in the shank-portion 33 of the operating-nut to permit rotation of the latter in the handle, but to prevent longitudinal displacement of the operating-nut. The lower end of the shaft 31 is provided with an axial internally-threaded aperture 37 to accommodate a screw 38 characterized by an enlarged head 39 for limiting the longitudinal displacement of the shaft relative to the nut 34. With the aforesaid shaft 31 mounted within the handle 15 and with the internally-threaded shank-portion 33 of the operating-nut engaged on the lower end of the shaft 31, the assembly-screw 38 is adapted to be inserted into the hollow operating-nut from the lower end thereof and up into the internally-threaded aperture in the lower end of the stem 31. Thus, as the shaft is moved longitudinally upwardly in the handle by rotation of the operating-nut 34, the enlarged head 39 of the screw will ultimately seat against the annular internal shoulder 40 of the hollow operating-nut so as to preclude further upward movement of the shaft, as indicated especially well in Fig. 3. For a pleasing appearance, the profile of the hollow operating-nut may be streamlined.

Mounted in the upper end of the handle for longitudinal movement therein is a yoke-member 41 of the blade-clamping means 18, the yoke-member comprising a substantially-cylindrical collar-portion 42, the external diameter of which corresponds substantially to the internal diameter of the aforesaid handle 15 so as to make a friction fit therein; and a pair of diametrically-opposed arms 43-43 extending upwardly from the collar-portion 42 of the yoke-member, each arm being provided at its upper extremity with a pair of transverse apertures 44-44. The overall length of the yoke-member 41 is such that when the latter is mounted in the upper end of the handle 15, the upper extremities of the arms 43-43 extend slightly above the plane of the outer face of the blade-supporting member 17.

The blade-clamping means 18 of the razor also comprises a pair of substantially-identical elongated clamps 45-45 (see Fig. 6), each having slightly concave and convex lower and upper surfaces respectively, the curvature of the lower concave surface corresponding substantially to the convex curvature of the outer face of the blade-supporting member 17. Each clamp is provided with a substantially-rectangular clearance-recess 46 which extends longitudinally of its upper surface and intersects the inner edge thereof. Moreover, each clamp 45 is provided on its inner edge with a pair of substantially-rectangular tongues 47-47 arranged thereon in longitudinally-spaced substantially-parallel relationship, the distance between the inner edges of each pair of tongues 47-47 being substantially equal to the distance between the outer faces of the

aforesaid pair of arms 43-43 of the yoke-member 41, the aforesaid arms 43-43 being adapted thus to engage between the tongues 47-47 of the respective clamps 45-45. Each tongue 47 is provided with a transverse aperture 48 adapted to accommodate a pin 49, the pin of each tongue 47 being in axial alignment with and adapted to engage in a corresponding transverse aperture 44 of one of the arms 43 to pivotally secure the corresponding clamp 45 thereto. Formed on the underside of each clamp 45 adjacent its two outer corners are integral downwardly-projecting protuberances 50-50 respectively adapted to engage in the notches 22-22 at corresponding corners of the blade-supporting member 17 when the clamps are swung down into their normal blade-clamping position, as hereinafter described. The upper end of the shaft 31 is reduced in cross section to provide an annular shoulder 51 and to form a reach 52 having at least two oppositely-disposed flat surfaces, the maximum transverse dimension of the reach being less than the transverse distance between the arms 43-43 of the aforesaid yoke-member 41 so that the reach 52 may extend freely therebetween. Fixedly secured to the upper end of the reach 52 by staking or equivalent means is clamp-locking means comprising a crest-plate 53 substantially equal in length to the clamps 45-45 of the blade-clamping means 18, and substantially equal in width to the distance transversely between the longitudinal shoulders of the clearance-recesses 46-46 of the respective clamps 45-45 when the latter are in their normal blade-clamping position, as shown especially well in Fig. 1. The thickness of the crest-plate 53 corresponds substantially to the depth of the clearance-recesses of the clamps 45-45 so that when the crest-plate 53 is engaged therein, its outer convex surface will be substantially continuous with the convex outer surfaces of the respective clamps 45-45. In order to insure smooth operation of the blade-clamping means and to preclude cramping, the underside of the crest-plate 53 is provided with a shallow relief-recess extending longitudinally between its oppositely-disposed edges.

Slidably mounted on the reach 52 of the shaft 31 is a substantially-rectangular elevating-cup 55 having side walls 56-56, end walls 57-57 and a bottom 58, the side walls 56-56 being slightly higher than the end walls 57-57, and provided with inwardly-sloping cam-faces 59-59 on their upper edges respectively as illustrated especially well in Fig. 7. The outside longitudinal and transverse dimensions of the elevating-cup are slightly less than the corresponding inside dimensions of the well 25 in the blade-supporting member 17, so that the elevating-cup may be mounted therein with freedom for movement vertically relative thereto, the sides and ends of the cup cooperatively engaging the corresponding sides and ends of the well to prevent rotation of the cup. The bottom 58 of the elevating-cup is provided with an elongated aperture 60, the length of which corresponds substantially to the distance between the outer faces of the upstanding-arms 43-43 of the yoke-member 41 and the width of the aperture corresponding substantially to the width of the arms, whereby the latter are adapted to be guided by the edges of the aperture 60 for substantially-vertical movement only therein, in the manner shown especially well in Fig. 5. It will be seen also from Fig. 5 and Figs. 1, 2 and 3, that the reach 52 of the shaft extends up through the aperture 60 in the bottom of the

elevating-cup between the arms 43-43 of the yoke-member, with the oppositely-disposed flat sides of the reach in sliding engagement with the corresponding edges of the aperture 69 to prevent rotation of the shaft; and that the width of the aperture 69 is less than the diameter of the annular shoulder 51 at the base of the reach 52, whereby the shoulder 51 forms a stop-abutment to limit longitudinal movement of the shaft relative to the cup. Thus, when the shaft is moved upwardly relative to the elevating-cup, the annular shoulder 51, which is normally spaced below the bottom of the cup to provide for lost motion therebetween, will be brought into engagement with the bottom of the cup to pick up the latter and carry it upwardly in the well 25 of the blade-supporting member and thereby swing the pivoted clamps upwardly, as illustrated in Fig. 3. In this connection, it should be pointed out that the distance between the inner faces of the end walls 57-57 of the elevating-cup corresponds substantially to the distance between the outer edges of each pair of clamp-tongues 47-47, so that as the cup moves upwardly to elevate the pivoted clamps, the tongues thereof may be accommodated within the cup, as illustrated in Fig. 3.

The razor blade 21 is shown especially well in Fig. 11 and is of the double-edge type formed of conventional razor-blade material and characterized by a substantially U-shaped slot 61 which extends longitudinally thereof and intersects one end of the blade. The width of the slot 61 corresponds substantially to the width of the elevating-cup, while the length of the slot is substantially equal to the distance from one end of the blade-supporting member to that end wall of the elevating-cup which is farthest therefrom. In order that the outer extremities of the blade may be held firmly in engagement with the blade-supporting member when clamped thereon, a notch 62 is formed in each corner of the blade opposite the corresponding notches 22 of the blade-supporting member so that when the clamps 45-45 are drawn down into blade-clamping relationship therewith, the protuberances 50 of the clamps will extend down through the notches in the corners of the blade into the corresponding notches 22 of the blade-supporting member.

By way of illustration, the elements of the razor may be assembled as follows. The upper end of the tubular handle 15 is staked or otherwise permanently secured in the aperture 29 in the bottom of the well 25, the upper end of which is staked or permanently secured in any suitable manner in the aperture of the blade-supporting member 17. The operating-nut 34 is mounted in the lower end of the handle by engaging the shank 33 of the operating-nut therein and securing the shank against longitudinal displacement relative to the handle by means of the annular indenture 32, in the manner hereinabove described. The yoke-member 41 is then slipped onto the upper end of the shaft 31 and slid down thereon so that its collar-portion 42 is below the annular shoulder 51 of its reach 52. Thereupon, the elevating-cup is engaged on the reach 52 of the stem and slid down thereon until the bottom of the cup seats on the shoulder 51. To facilitate assembling the clamps 45-45 on the upper ends of the arms 43-43 of the yoke-member 41, the latter may be moved upwardly on the shaft so that the upper ends of the arms 43-43 will project above the upper edges of the elevating-cup. Thus, the pins 49 may be readily inserted in the

axially-aligned apertures of the clamp-tongues and the arms to pivotally secure the clamps thereto. The crest-plate 53 is then secured on the upper extremity of the reach 52 of the shaft 31 by any suitable fastening-means such as, for example, by rivet-means, staking or brazing. This entire assembly, that is to say, the shaft, the yoke-member, the elevating-cup, the clamps and the crest-plate, is then mounted in the handle 15 of the razor by introducing the externally-threaded end of the shaft into the upper end of the handle, and moving it downwardly therein until the lower end of the shaft is below the internal annular shoulder 40 of the operating-nut. Thereupon, the screw 38 is engaged in the axial aperture in the lower end of the shaft to prevent withdrawal of the shaft from the handle 15. With the elements assembled in the manner hereinabove described, the collar-portion 42 of the yoke-member 41 will be slidably engaged in the upper end of the handle 15 but below the annular shoulder 51 of the shaft 31, while the elevating-cup will be engaged in the well 25 of the blade-supporting member 17. It will be understood that the method of assembly hereinabove described is peculiar to the specific structure shown herein for illustrating the invention but that variations on the method of assembly are included within the purview of the invention in accordance with modifications of the structure shown.

In order to mount a razor blade 21 on the head of the razor, the operating-nut 34 is rotated in a clockwise direction, thereby to move the shaft upwardly in the handle initially to move the crest-plate upwardly away from the blade-supporting member 17, the initial upward movement of the shaft occurring without affecting either the yoke-member or the elevating-cup, inasmuch as the former forms a relatively-snug friction fit in the upper end of the handle, and the annular shoulder of the shaft is below the bottom of the elevating-cup. However, when the annular shoulder 51 of the shaft moves up into engagement with the bottom of the elevating-cup, the latter is also moved upwardly out of the well 25, whereupon the cam-faces 58-59 on the upper edges of the cup engage and pivot the clamps 45-45 upwardly and inwardly, the clamps pivoting about the pins 49 engaged in the upper ends of the arms 43 of the yoke-member. The upward swinging movement of the clamps continues until the clamps engage the underside of the crest-plate, whereupon the elevating-cup is held against further upward movement relative to the yoke-member. Thereafter, additional upward movement of the shaft and the elevating-cup positively forces the yoke-member upwardly relative to the handle into the well 25 of the blade-supporting member, as indicated in Fig. 3. Thus, the maximum upward displacement of the clamps corresponds to the upward movement of the shaft plus the upward displacement of the yoke-member, whereby there is provided ample space between the upper surface of the blade-supporting member 17 and the undersides of the clamps 45-45 not only for cleaning the parts of the razor, but for mounting the blade 21 on the blade-supporting member, which is done by sliding the slotted end of the blade past the elevating-cup. By reversing the rotation of the operating-nut, that is to say, by turning the latter in a counterclockwise direction, the downward movement of the shaft 31 will pull the yoke-member, elevating-cup and clamps downwardly

so that the yoke-member is drawn down out of the well 25 into the upper end of the handle. Further downward movement of the shaft carries the elevating-cup to substantially the bottom of the well, the upper edges of the cup being at this time substantially flush with the upper surface of the blade-supporting member 17. The upper ends of the arms 43 of the yoke-member 41 will then project above the upper edges of the elevating-cup so that additional movement of the shaft downwardly in the handle will cause the crest-plate to positively cam the clamps 45-45 outwardly and downwardly into clamping relationship with the blade mounted on the upper surface of the blade-supporting member 17, the crest-plate finally seating in the opposed clearance-recesses 46-46 of the clamps 45-45 to lock the clamps in blade-clamping position.

The razor of this invention thus provides a unitary structure which, having once been assembled, does not require the complete separation of any of its elements for the purpose of inserting a blade in the head of the razor, or removing a blade therefrom. Moreover, when the clamping-elements of the razor-head are swung open, the elevating-cup provides a shield around the upper end of the well to prevent the accumulation of soap and other undesirable materials in the head of the razor, thereby facilitating cleaning and drying the several parts of the razor-head.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A safety razor having a tubular handle; a blade-supporting member secured thereon; a pair of blade-clamping members; a movable yoke member to which the blade-clamping members are pivoted; an elevating member engageable with the blade-clamping members; manually-operable means mounted in said handle and arranged to actuate the elevating member to move said pair of blade-clamping members substantially simultaneously out of blade-clamping position; and a crest-plate constructed and arranged to be actuated by said manually-operable means to return and lock said clamping members in blade-clamping position.

2. A safety razor having a tubular handle; a blade-supporting member secured thereon; a movable yoke member; a pair of blade-clamping members pivotally mounted on the yoke member; manually-operable means including a shaft mounted in said handle and arranged to be moved perpendicularly with respect to said blade-supporting member; an elevating member in contact engagement with said pair of blade-clamping members and arranged to be actuated by said shaft to move said pair of blade-clamping members substantially simultaneously out of blade-clamping position; and a crest-plate carried by said shaft and arranged to be actuated thereby to engage and positively move said blade-clamping members back into blade-clamping position.

3. A safety razor having a tubular handle; a blade-supporting member secured thereon, said blade-supporting member being provided with a well; a movable yoke member; a pair of blade-

clamping members pivoted to the yoke member; a cup-shaped member movably disposed in said well and arranged to engage the blade-clamping members; manually-operable means mounted in said handle and arranged to move the cup-shaped member longitudinally so that the cup-shaped member, in one position, allows both blade-clamping members to be in a plane substantially parallel to the plane of said blade-supporting member and, in another position, supports said clamping members at substantially equal divergent angles to said plane of said blade-supporting member; and locking means including a crest-plate carried by said manually-operable means and arranged to be actuated thereby to return and lock said clamping members in the first mentioned position.

4. A safety razor having a tubular handle; a blade-supporting member secured thereon, said blade-supporting member being provided with a substantially-central well having an apertured bottom; a cup-shaped member movably disposed in said well; a movable yoke member extending into said well from the aperture in the bottom thereof; a pair of blade-clamping members pivotally mounted on the yoke member and in engagement with the cup-shaped member; manually-operable means mounted in said handle and arranged to move said cup-shaped member longitudinally in said well so that the cup-shaped member, in one position, allows the blade-clamping members to be in a plane substantially parallel to the plane of said blade-supporting member and, in another position, supports said clamping members at substantially equal divergent angles to said plane of said blade-supporting member; and locking means including a crest-plate carried by said manually-operable means and arranged to be actuated thereby to positively return and lock said clamping members in the first-mentioned position.

5. A safety razor having a tubular handle; a blade-clamping member secured thereon, said blade-clamping member being provided with a substantially-central well having an apertured bottom; a slideable yoke member extending into said well from the aperture in the bottom thereof; a pair of blade-clamping members pivotally mounted on the yoke member; manually-operable means including a shaft mounted in said handle and arranged to extend up through the aperture in the bottom of said well and to be moved relative to said blade-supporting member; a cup-shaped member arranged to seat in said well and to be actuated by movement of said shaft relative thereto to engage and move said pair of clamping members substantially simultaneously out of blade-clamping position; and locking means including a plate secured to said shaft and arranged to be actuated thereby to engage said clamping members initially to positively move and subsequently to lock said clamping members back into blade-clamping position.

6. A safety razor having a tubular handle; a blade-supporting member secured to the upper end of said handle; a movable yoke member mounted in the upper end of said handle; a pair of blade-clamping members pivoted to the yoke member; an elevating cup slidably mounted on the arms of the yoke member and arranged to engage the blade-clamping members; manually-operable means mounted in said tubular handle and arranged to be moved longitudinally with respect thereto to move said cup-shaped member and pivot said pair of clamping members sub-

stantially simultaneously out of blade-clamping position; and means including a plate carried by said manually-operable means and arranged to engage said blade-clamping members to positively move said clamping members back into blade-clamping position.

7. A safety razor having a tubular handle; a blade-supporting member secured to the upper end of said handle, said blade-supporting member having a substantially-central well provided with an apertured bottom; a yoke member having a longitudinal hole therein movably mounted in the upper end of said tubular handle and arranged to project up into the well through the aperture in the bottom thereof; a pair of blade-clamping members pivoted to the yoke member; an elevating cup having an apertured bottom disposed in said well and slidably mounted on the arms of the yoke member; manually-operable means including a shaft mounted in said handle and arranged to extend through the hole in said yoke member and initially to be moved relative to said yoke member to engage said elevating cup so that the elevating cup, in one position, allows said blade-clamping members to be on a plane substantially parallel to the plane of said blade-supporting member and, in another position, supports said clamping members at substantially equal divergent angles to said plane of said blade-supporting member; and means including a plate mounted rigidly on said shaft arranged to engage and to positively move and subsequently to lock said blade-clamping members back in the first mentioned position.

8. A safety razor having a tubular handle; a blade-supporting member secured thereto; a movable yoke member mounted in said tubular handle; a pair of blade-clamping members pivoted to the yoke member and provided with longitudinal recesses in the outer faces thereof; a movable cup-shaped member slidably mounted on the arms of the yoke member; manually-operable means mounted in said handle and arranged to move the cup-shaped member to pivot said pair of blade-clamping members from a position where they are in a plane substantially parallel to the plane of said blade-supporting member to a position where they are supported by said cup-shaped member at substantially equal divergent angles to said plane of said blade-supporting member; and locking means including a crest-plate carried by said manually-operable means, said crest-plate being arranged to engage and lock said clamping members in the first mentioned position; said longitudinal recesses in the outer faces of said clamping members being constructed and arranged to accommodate said crest-plate when said locking means is in locking engagement with said clamping members so that the outer faces of said clamping members and the outer face of said crest-plate form a substantially smooth and unbroken surface.

9. A safety razor having a tubular handle; a blade-supporting member secured thereon, said blade-supporting member being provided with an embossment on the upper surface thereof with notches in the four corners of said embossment; a movable yoke member mounted in the upper end of said tubular handle; a pair of blade-clamping members pivotally mounted on the movable yoke member, each of said blade-clamping members having a pair of protuberances thereon to engage with the notches in said embossment in blade-clamping position; a movable cup-shaped member whose oppositely-disposed

edges are arranged to be in engagement with the pair of blade-clamping members; manually-operable means including a shaft mounted in said handle and movable longitudinally therein to engage and move said cup-shaped member so that said clamping members are pivoted substantially simultaneously out of blade-clamping position; a blade adapted to be clamped between said blade-supporting member and said clamping members, said blade having a substantially rectangular slot open at one end and substantially equal in width to the corresponding dimension of said cup-shaped member, to permit said blade to be horizontally moved into position around said cup-shaped member, said blade being provided with notches in each corner thereof in alignment with the corresponding notches in the corners of said embossment of said blade-supporting member; and means including a clamping plate carried by said shaft and arranged to engage and positively return said clamping members to blade-clamping position to hold and lock said blade against said blade-supporting member.

10. A safety razor having a tubular handle; a blade-supporting member secured to the upper end of said handle; a yoke member movably mounted in the upper end of said tubular handle; a pair of blade-clamping members pivoted to the yoke member; an elevating cup guided by the arms of said yoke member and arranged to engage said clamping members; manually-operable means mounted in said tubular handle and movable longitudinally with respect thereto to engage and move said elevating cup, said elevating cup in turn moving said yoke member outwardly of said handle and pivoting said blade-clamping members from a position of being in a plane substantially parallel to the plane of said blade-supporting member to a position of being at substantially equal divergent angles to said plane of said blade-supporting member; locking means, including a crest-plate rigidly affixed to the end of said shaft, said plate being arranged to return said clamping means, elevating cup and yoke member to the first mentioned position and to lock said clamping members in blade-clamping position with respect to said blade-supporting member; and a nut-member mounted on said tubular handle and arranged to engage said shaft for moving the manually-operable means longitudinally in said handle.

11. A safety razor having a tubular handle; a blade-supporting member secured on the upper end thereof, said blade-supporting member being provided with a substantially-central well having an apertured bottom; a pair of blade-clamping members; a movable yoke member mounted in the upper end of said handle and arranged to extend up into said well through the aperture in the bottom thereof to pivotally support said pair of blade-clamping members; a cup-shaped member slidably mounted on that portion of the yoke member extending into said well and positioned therein to engage said blade-clamping members, said cup-shaped member having cam-surfaces on the upper oppositely-disposed edges thereof; manually-operable means including a shaft mounted in said tubular handle and arranged to move said cup-shaped member upwardly relative to said well to engage its cam-surfaces against said pair of clamping members and substantially simultaneously move said clamping members upwardly out of blade-clamping position, said shaft having a reach engaged

in and extending up through the aperture in the bottom of said well, said reach being movable perpendicularly with respect to said blade-supporting member, and a crest-plate fixed on the upper end of said reach, said crest-plate being arranged to engage said clamping members as said shaft is moved down initially and to positively return said clamping members, cup-shaped member and yoke member to blade-clamping position and subsequently to lock said clamping members down into blade-clamping position.

12. A safety razor having a tubular handle; a blade-supporting member secured on the upper end thereof; said blade-supporting member being provided with a substantially-central well having an apertured bottom; a pair of blade-clamping members; a yoke member mounted with a friction fit in the upper end of said handle and arranged to extend up into said well through the aperture in the bottom thereof to pivotally support said pair of blade-clamping members; a cup-shaped member movably disposed in said well and engageable with said blade-clamping members, said cup-shaped member having cam-surfaces on the upper oppositely-disposed edges thereof; manually-operable means including a shaft mounted in said tubular handle and arranged to move said cup-shaped member upwardly relative to said well to engage its cam surfaces against said pair of clamping members and move the latter substantially simultaneously upwardly out of blade-clamping position, said shaft having a reach engaged in and extending up through the aperture in the bottom of said well, said reach being movable perpendicularly with respect to said blade-supporting member; a crest-plate fixed on the upper end of said reach, said crest-plate being arranged to engage said clamping members as said shaft is moved down initially to positively move and subsequently to lock said clamping members down into blade-

clamping position; and a nut-member rotatably mounted on the lower end of said handle, said nut-member being threadedly engaged with the lower end of said shaft so as to move said shaft up and down in said handle.

13. In a safety razor: a tubular handle; a blade-supporting member secured thereto; a yoke member movably mounted in said handle; a pair of blade-clamping members pivotally mounted on said yoke member; an elevating member movably mounted in said supporting member; actuating means in said handle to move said elevating member, said cup-shaped member causing said clamping members to be substantially simultaneously pivoted out of blade-clamping position and said yoke member to be moved outwardly of said handle during such movement; and a plate member actuated by said actuating means to move said yoke and elevating members inwardly of said handle and positively return said clamping members to blade-clamping position.

14. A razor as defined in claim 13 wherein said blade-supporting member and blade-clamping members are provided with cooperating aligning means to properly position a razor blade therebetween.

PAUL J. GRAYBILL.
